UNITED STATES PATENT OFFICE.

RALPH W. DUDDING, OF MINNEAPOLIS, MINNESOTA.

LIFTING-JACK.

1,158,903.

Specification of Letters Patent.

Patented Nov. 2, 1915.

Application filed July 29, 1914. Serial No. 853,828.

To all whom it may concern:

Be it known that I, RALPH W. DUDDING, citizen of the United States, residing at Minneapolis, in the county of Hennepin and State of Minnesota, have invented certain new and useful Improvements in Lifting-Jacks; and I do hereby declare the following to be a full, clear, and exact description of the invention, such as will enable others skilled in the art to which it appertains to make and use the same.

My invention has for its object to provide a lifting jack, by means of which a load may be raised and lowered vertically, and caused to travel laterally simultaneously with said vertical movement.

To the above ends, generally stated, the invention consists of the novel devices and combinations of devices hereinafter described and defined in the claims.

In the accompanying drawings, which illustrate the invention, like characters indicate like parts throughout the several views.

Referring to the drawings:—Figure 1 is a view of the improved lifting jack, principally in side elevation, with some parts sectioned on the line $x^1 x^1$ of Fig. 4. Fig. 2 is a plan view of the improved lifting jack; Fig. 3 is a longitudinal vertical section, taken on the line $x^3 x^3$ of Fig. 2; Fig. 4 is a left hand end elevation of the improved lifting jack, with respect to Fig. 3; and Fig. 5 is a right hand end elevation of the improved lifting jack, with respect to Fig. 3.

The numeral 1 indicates a base casting having integrally formed therewith a pair of laterally spaced skeleton side flanges 2. Mounted between the side flanges 2, for independent oscillatory movement, are a lifting segment 3 and a lowering segment 4.

These segments are journaled on a heavy bolt 5 anchored in the upper transverse portions of the side flanges 2. Each segment has formed in its periphery a double row of laterally spaced gear teeth 6. On the inner extremities of the segments 3—4, are pivotally mounted shoes 7 and 8, respectively, for supporting the load. These shoes extend radially outward of the peripheries of the

50 segments, and have their outer and upper portions roughened or serrated, to prevent the load from slipping thereon. As best shown in Fig. 2, the hub of the lowering segment 4 is bifurcated, and the hub of the lifting segment 3 works there-between.

The segment 3 is raised by a lever 9, and

the segment 4 is lowered by a lever 10, said levers having sockets 11 adapted to receive and detachably hold a lever extension 12. These levers 9 and 10 are mounted between laterally spaced lugs 13, integrally formed with the base 1 and fulcrumed on heavy pins 14, mounted in said lugs. Carried by each lever 9 and 10 is a pair of gravity held, upwardly projecting dogs 15 and 16 respectively, arranged for coöperation with the teeth 6 of the respective segments 3 and 4. As best shown in Fig. 1, the lower ends of the dogs 15 and 16 are bifurcated and the prongs thereof embrace the respective levers 9 and 10 and are pivotally secured thereto by pins 17. The dogs of each pair are located on opposite sides of the respective fulcrum pins 14, so that when the levers 9 and 10 are operated, one dog of each pair moves down, while the other moves up. Obviously, the upwardly moving dog 15 imparts a step by step lifting movement to the segment 3.

To lower the shoe 8, it is necessary to alternately render the dogs 16 inoperative. As shown, this is accomplished by a hand operated lever 18, having at its lower end a tri-angular head 19, mounted between a pair of opposing leaf springs 20, anchored at their ends to the dogs 16. These springs 20, yieldingly hold the free end of the lever 18 at one of its two extreme positions. The free end of the lever 18 is arranged to engage the intermediate portions of the dogs 16 and hold the engaged dog out of engagement with the teeth 6 of the segment 4. Stops 21, on the side flanges 2 are provided to limit the outward swinging movement of the dog 16. Obviously, the downwardly moving dog carries the load, in lowering the shoe 8.

Integrally formed with each segment 3 and 4, is a pair of laterally and oppositely projecting stop lugs 22, arranged to engage stop shoulders 23 formed in the upper transverse portion of the side flanges 2, to limit the oscillatory movements of said segments toward each other, and to prevent the shoes 7 and 8 from passing from beyond dead centers.

From the foregoing description, it is evident that the load 7 may be lifted by the segment 3, and, at the same time, moved laterally. During this movement of the load, the shoe 7 may travel substantially 90 degrees. If it is desirable to further move the load laterally, the same may be trans-

ferred to the segment 4 and lowered thereby into substantially its original horizontal position. This segment 4 may also move substantially 90 degrees. To transfer the 5 load from the side shoe 8, the segment 4 is moved upward, into engagement with the load Z. The segment 3 is then lowered, to carry its shoe 7 out of engagement with the load and leave on the shoe 8.

10 What I claim is:—

1. A lifting jack having a pair of reversely acting lifting elements independently mounted for vertical and lateral movements, one of said lifting elements arranged 15 to pick up the load and deliver the same on to the other of said lifting elements.

2. A lifting jack having a pair of reversely acting lifting elements independently mounted for vertical and lateral movements, one of said lifting elements arranged 20 to pick up the load and deliver the same on to the other of said lifting elements, and means for independently moving said elements.

25 3. A lifting jack, comprising a support, a lifting segment journaled on said support, a shoe pivoted to said segment, at the periphery thereof and engaged to be held by the load in a horizontal position above its 30 pivotal support, and means for moving said segment.

4. A lifting jack, comprising a support, a toothed lifting segment journaled on said support, a load supporting element pivoted 35 to said segment and a dog-equipped lever fulcrumed on said support and coöperating with the teeth of said segment for imparting the step by step movement thereto.

5. A lifting jack, comprising a support, 40 a toothed lifting segment journaled on said support, a shoe carried by said segment, at the periphery thereof, a lever fulcrumed on said support, a pair of opposing dogs carried by said lever and coöperating with the 45 teeth of said segment, and a stop limiting the oscillatory movement of said segment.

6. A lifting jack, comprising a support,

a lifting segment and a lowering segment journaled on said support, for oscillatory movements, said lifting segment arranged to pick up the load and deliver the same on to said lowering segment, and means for independently moving said segments.

7. A lifting jack, comprising a support, 55 a lifting segment and a lowering segment journaled on said support, for oscillatory movements, a shoe carried on the inner extremity of each of said segments, and means for moving said segments, the shoe on said lifting segment arranged to pick up the 60 load and deliver the same on to said lowering segment.

8. A lifting jack, comprising a support, 65 a toothed lifting segment and a toothed lowering segment journaled on said support, for independent oscillatory movements, a shoe carried on the inner extremity of each of said segments, the shoe on said lifting segment arranged to pick up the load and deliver the same on to said lowering 70 segment, and dog-equipped levers fulcrumed on said support and coöperating with the teeth of said segments, for independently moving the same.

9. A lifting jack, comprising a support, 75 a toothed lifting segment and a toothed lowering segment journaled on said support, for independent oscillatory movements, a shoe carried on the inner extremity of each of said segments, the shoe on said lifting segment arranged to pick up the load and deliver the same on to said lowering segment, dog-equipped levers fulcrumed on said support and coöperating with the 80 teeth of said segments, for independently moving the same, and stops for limiting the oscillatory movements of said segments 85 toward each other.

In testimony whereof I affix my signature in presence of two witnesses.

RALPH W. DUDDING.
